EXHAUST STEAM HEATER

Application filed October 9, 1929, Serial No. 398,515, and in Great Britain November 23, 1928.

This invention relates to exhaust steam heaters and its object is to provide an improved construction and arrangement thereof.

5 According to the present invention, we provide an exhaust steam heater comprising one or more heating units having a bank, or banks, of parallel, or substantially parallel, tubes, and headers with which the said tubes communicate so that the exhaust steam to be reheated is conveyed by the said headers and tubes in parallel, or substantially parallel, streams, through a heating space wherein in the said headers and tubes are exposed to 10 boiler flue gases or like heating medium.

A further feature of our invention is to provide an exhaust steam heater comprising one or more heating units having a combined inlet and outlet header, a transfer or 20 return header, a bank or row of outgoing tubes leading from the said header, a bank or row of return tubes entering the said header, and a transfer or return header uniting the free ends of said outgoing and re- 25 turn tubes.

In accordance with another feature of the invention, the exhaust steam heater comprises one or more heating units having superposed rows of steam tubes arranged with 30 headers therefor in the path of boiler flue gases or like heating medium, the tubes of each row being staggered or placed out of alignment with respect to the tubes of the row or rows therebelow.

35 More specifically, our exhaust steam heater has one or more heating units arranged in the upper part of a boiler uptake and comprising a bank, or banks, of parallel or substantially parallel, steam tubes, and headers with which the said tubes are connected so that both the headers and tubes are completely enclosed within the uptake and extend across the whole or the most part of the cross-section thereof. Preferably the 40 heating unit or units is or are arranged above an air heater in the uptake.

A preferred embodiment of our invention, as applied to an exhaust steam heater for use in the uptake of marine boilers with the 45 "Howden" forced draft system, will now be

described, by way of example, with reference to the annexed drawings, in which:

Fig. 1 is a side view of the exhaust steam heater with the boiler uptake casing in section. 55

Fig. 2 is a plan view of the heater with the uptake casing removed.

Fig. 3 is a cross-sectional view of the heater, taken on the line A—B (Fig. 2).

Referring to the drawings:

The boiler uptake casing 1 accommodates in known manner an air heater having vertical air heating tubes 2 through which the boiler flue gases pass upwards. Above the upper ends of the tubes 2, the exhaust steam 65 heater described hereinbelow is located, sufficient clearance being left between the heater and the upper ends of the tubes 2 to permit the unobstructed passage of the flue gases through and around the whole heater as hereinafter explained. 70

The exhaust steam heater comprises two similar heating units *a* and *b* connected in series by elbow pipes 3. Each units comprises a combined inlet and outlet header 4, and a 75 transfer or return header 5, both of these headers being box shaped. Each of the combined inlet and outlet headers 4 is provided with a dividing wall 6 (see Fig. 3) which separates the interior of the header into a lower space 7 and an upper space 8. In the header 4 of the heating unit *a*, the lower space 7 constitutes the inlet chamber of the header and communicates with a pipe 9 whereby the 80 exhaust steam for reheating enters. The upper space 8 of the unit *a*, on the other hand, communicates (see Fig. 3) with the elbow pipe 3 whereby the exhaust steam passes outwards from the unit *a* to the unit *b*.

This arrangement is reversed in respect of the heating unit *b*, the upper space of the header 4 in this case constituting the inlet chamber into which leads the elbow pipe 3 and the corresponding lower space constituting the outlet chamber from which the reheated exhaust 90 steam escapes by the outlet pipe 10. In contrast to the above described partitioning of the headers 4, the interior of both transfer or return headers 5 is left plain, i. e., is not divided into separate compartments. 95

The lower space 7 of each combined inlet and outlet header 4 communicates with the corresponding transfer header 5 by parallel tubes 11 (six in number, as shown most clearly in Fig. 3). The transfer header 5 communicates, in turn, with the upper space 8 of the corresponding header 4 by five parallel tubes 12. The tubes 11 and 12 are fitted in the headers 4, 5 by any suitable means, as for instance, by expanding the tube ends in the headers, or by screwing them into the headers.

The complete exhaust steam heater constituted by the headers 4 and 5, tubes 11 and 12, and elbow pipes 3, is supported above the air-heating tubes 2 by wrought iron or like metal clips each of which is formed by a bottom strip 13 of angle section secured at the ends to the uptake casing 1, and a keeper strap 14 which extends over the tubes 11, 12 and is bolted to the corresponding bottom strin 13.

The direction of flow of the exhaust steam through the heater is shown in Figs. 1 and 2 by the arrows. As will be apparent from the foregoing, the steam to be reheated flows from the lower space 7 of the header 4 of the unit *a*, through the six bottom tubes 11, thence returning by way of the transfer header 5, through the five top tubes 12 to the upper space 8 of the first mentioned header 4. Thereafter, the partially reheated steam passes over the elbow pipes 3 into the upper space of the header 4 of the unit *b*, and thence through the top tubes 12, transfer header 5, and bottom tubes 11 into the lower space of the last mentioned header 4 from which the completely reheated steam escapes by the outlet pipe 10.

It will be seen from Fig. 3 that the top tubes 12 of the heating units are arranged in staggered relationship with respect to the bottom tubes 11, i. e., a tube 12 is arranged directly above each space between the tubes 11. By this arrangement, the top and bottom rows of exhaust steam tubes exert a baffle effect on the ascending flue gases, sufficient to obtain a more thorough exchange of heat between the flue gases and exhaust steam than is obtainable by arranging each tube 12 of the top row directly above a tube 11 of the bottom row.

The reheated steam may be used for any desired purpose in known manner, as for instance, in marine work, for heating cabins or for the low pressure stage of the engine.

It will be understood that various modifications may be made in the invention without departing from the scope of the claim. For example, three or more heating units, instead of two units as described, can be connected in series and an exceptionally large heating surface is thereby provided for the steam. Any convenient method may be used for connecting the heating units together. An alter-

native method to that previously described consists of fitting to the outlet of one unit a male joint which is adapted to register with a female joint on the inlet of the adjacent unit, or vice versa, the two being secured together with tie bolts which pass through the two units. The joint is of course made steam tight in well known manner.

Our invention is particularly adapted for use with the well known "Howden" forced draft system, one mode of using the invention with which system has been described above, and is also adapted for use with boilers fitted with high pressure superheater where the exhaust steam heating elements have to be placed high in the boiler uptakes.

We claim:—

The combination with a boiler of an exhaust steam heater mounted in the uptake adjacent the outlet ends of flue gas tubes, said heater comprising, two interconnected heating units, each unit comprising a divided header forming inlet and outlet compartments for the steam to be heated, a first row of parallel steam tubes let into the inlet compartment, a second row of parallel steam tubes let into the outlet compartment, said first and second rows each extending in planes substantially parallel to that containing the outlet ends of the flue gas tubes whereby the flue gases impinge on the steam tubes immediately after leaving the flue gas tubes and without changing their direction of flow, a single compartment header uniting the free ends of the steam tubes in said rows, but the first row of steam tubes in one unit being nearer the outlet ends of the flue gas tubes than the second row, and the second row of steam tubes in the other unit being nearer the outlet ends of the flue gas tubes than the first row in that unit, whereby the steam is caused to flow, firstly in a row of steam tubes nearer the outlet ends of the flue gas tubes, then in two rows in series further away from these outlet ends, and finally in a row nearer these outlet ends, the steam in the final stage, therefore being heated by the hottest flue gases.

In testimony whereof we affix our signatures.

JAMES NEWBY WYNDHAM.
STEPHEN LEYSHON WYNDHAM.
